UNITED STATES PATENT OFFICE.

GEORGE L. PITTMAN, OF BELMONT, OHIO.

THRASHING-MACHINE.

SPECIFICATION forming part of Letters Patent No. 352,148, dated November 9, 1886.

Application filed April 16, 1886. Serial No. 199,111. (No model.)

To all whom it may concern:

Be it known that I, GEORGE L. PITTMAN, a citizen of the United States, residing at Belmont, in the county of Belmont and State of Ohio, have invented a new and useful Improvement in Thrashing-Machines, of which the following is a specification, reference being had to the accompanying drawings.

This invention relates to devices for shaking the straw on the carrier of a thrashing-machine in order to dislodge the loose grains therefrom; and it consists in the peculiar construction and combination of devices, that will be more fully set forth hereinafter, and particularly pointed out in the claims.

In the drawings, Figure 1 is a side elevation of a portion of a thrashing-machine provided with my improved device for shaking the straw. Fig. 2 is a top plan view of my invention. Fig. 3 is a sectional view of the same, taken on the line *x x* of Fig. 2.

In Fig. 1, *A* represents the usual straw-carrier of a thrashing-machine. Above this carrier, at a suitable point in the sides of the frame *B* of the machine, is journaled a pair of crank-shafts, *a* and *b*, each of which is provided throughout its length with a series of oppositely-extending cranks, *c*. The shaft *a* is provided on one end with a band-pulley, *d*, and a spur-wheel, *e*, and the shaft *b* is provided on one end with a spur-wheel, *f*, which is of the same diameter and has the same number of teeth as the wheel *e*, and meshes therewith, so that when the shaft *a* is rotated the shaft *b* will be also rotated at the same rate of speed and in the opposite direction. The shafts are so geared that when in their initial position their respective cranks will be parallel with each other, as shown in Fig. 3.

To the wrists of the cranks of the shaft *b* are journaled a series of blocks, *g*, to which are rigidly secured a series of fingers, *h*, which are made of metallic rods, and have each a forwardly-extending arm, *i*, and a rearwardly-extending stem, *k*. The arms *i* are bent downwardly, and have their lower ends curved forwardly, as shown in Figs. 1 and 3, and the stems *k* of the said fingers pass through longitudinal openings which are made in blocks *l*, that are journaled on the wrists of the cranks of the shaft *a*, the said stems *k* being free to reciprocate in the openings in the said blocks.

The fingers *h* are adjusted with relation to the carrier of the thrashing-machine so that their lower ends just clear the upper sides of the said carrier when the lower ends of the fingers are depressed to their lowest position.

The operation of my invention is as follows: When the thrashing-machine is in operation, the shafts *a* and *b* are rotated by being connected to a suitable driving-pulley on the machine by means of an endless belt, *m*, and the band-pulley on the shaft *a*. When the said shafts are in their initial position, (shown in Fig. 2,) the lower ends of the arms of the fingers are substantially in a horizontal line with each other at a considerable distance above the carrier, as shown in dotted lines in Fig. 3. When motion is imparted to the said shafts, the shaft *a* rotates in the direction of the arrow *m*, (shown in Fig. 3,) and the shaft *b* rotates in the contrary direction, as indicated by the arrow *n* in the said figure. The said shafts are arranged closely together, so that their cranks describe intersecting circles, and thereby, when they rotate, the fingers are moved from a horizontal to nearly a vertical position and back again. When the shafts have moved through one-fourth of a circle, the cranks on the shaft *a* assume a vertical position, and those on the shaft *b* assume the same position, by which means one-half of the fingers have their arms raised to their highest point from the carrier, and the remaining half of the said fingers intermediate between the others have their arms depressed nearly to a vertical position, and with their points almost in contact with the carrier and engaging with the straw thereon. Continued rotation of the shafts causes the engaging ends of these arms to move forwardly for a very slight distance with the carrier and then upwardly, while the intermediate series of fingers descend and come in contact with the straw on the carrier, their movement being precisely the same as that of the first series, but one-half a revolution later as to time. The outer end of each arm of the fingers describes two arcs of a circle, forming the sides of a crescent. As the shafts *a* and *b* are rotated at a very high rate of speed when the thrashing-machine is in operation, and as the straw is subjected to the "kicking" action of the two sets of fingers during its passage on the carrier, it is very violently agitated there-

by, thus causing all the loose grains on the straw to be dislodged therefrom.

It will be observed that the cranks of one shaft work within the cranks of the adjacent shaft, so that the cranks intersect each other's orbits, and thus the fingers carried by the shafts are caused to be tilted to nearly a vertical position, thereby causing the fingers to enter the straw point downward and get a firm hold on the straw. It also enables the fingers to be made much shorter, consequently reducing the friction and the leverage of the fingers on the crank-shafts, and enabling the machine to run much more easily.

Having thus described my invention, I claim—

1. In a thrashing-machine, the combination, with the straw-carrier A, of the shafts *a b*, geared together and each provided with the series of oppositely-extending cranks, the blocks *g l*, journaled on the wrists of the cranks of the respective shafts, and the fingers *h*, hav-

ing their stems suitably connected to blocks *g* and passed through openings in blocks *l*, whereby the said stems are free to reciprocate in the blocks *l* when the machine is in operation, as set forth.

2. In a thrashing-machine, the combination, with the straw-carrier A, of the parallel shafts *a b*, geared together and provided with oppositely-extending cranks, and fingers attached to one of the cranks of each shaft, said shafts being arranged close together, so that their cranks describe intersecting circles, whereby when the shafts rotate the fingers are moved from a horizontal to nearly a vertical position, as set forth.

In testimony that I claim the foregoing as my own I have hereto affixed my signature in presence of two witnesses.

GEORGE L. PITTMAN.
